DISPLAY STAND

Ettore Neglia, San Giorgio, Italy, assignor to P. Ferrero
& C.S.p.A., Alba, Cuneo, Italy, an Italian joint stock company

Filed June 27, 1969, Ser. No. 17,923

Term of patent 14 years

Int. Cl. D6—01

U.S. Cl. D80—9

FIG. 1

FIG.2

FIG.6

FIG. 5

FIG. 4

FIG. 3

FIG. 1 is a perspective view of a display stand showing my new design;

FIG. 2 is a front elevational view thereof;

FIG. 3 is an elevational view taken from one side thereof;

FIG. 4 is a rear elevational view thereof;

FIG. 5 is an elevational view taken from the side opposite that shown in FIG. 3; and

FIG. 6 is a top plan view thereof.

I claim:

The ornamental design for a display stand, as shown.
